UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed September 6, 1924. Serial No. 736,216.

This invention relates to machines for typing upon printed webs.

Usually articles that are ordered are grouped in different departments, and, in order to enable a number of departments to work on several parts of an order simultaneously, the original order is split up in the copying.

The present invention permits the printing of successive invoice forms on a web, permitting different lengths of forms to be used. The usual line-spacing mechanism of the typewriter need only be employed to advance the work-sheet from the first to the second writing lines on the forms, and at all other times the much quicker method of advancing the work-sheet by drawing it out of the machine with the fingers may be used; the present invention providing means for gaging variably the leading form on the work-sheet, after that form has been completed, and for severing a form of that length from the work-sheet, simultaneously with the bringing of the first writing line of the second form of the same length to the printing point.

This invention also provides means which may be mounted on any Underwood typewriting machine without alteration thereof, for holding the rapidly advanced web in its true right-angle relation to the platen, and for tearing off the web. Means are provided for truing the tearing-off knife, and means are also provided for adjusting the width of the device so as to be attachable to varying widths of machines.

Another feature of the present invention is to provide such an arrangement of knife-bar that the cutting edge thereof will be supported upon a bias with respect to the paper-table so that its cutting edge is nearest to the table and its blunt edge farthest therefrom. This permits some friction to occur between the knife and the work-sheet introduced into the space between the cutting edge of this knife and the adjacent surface of the table, and gives other advantages.

Other features and advantages will hereinafter appear.

In the accompanying drawings,

Figure 1 is a top plan view of a machine showing the parts of my invention mounted in position thereon.

Figure 2 is a transverse sectional elevation, partly in section, of Figure 1.

Figure 3 is a fragmental detail view, partly

in section, of the adjustable connections between knife and the support therefor.

Referring to the drawings, which are merely illustrative of my invention, 10 designates the usual platen fast upon the platen-shaft 11, the platen 10 being rotatively mounted in suitable bearings in the usual platen-frame which is provided with the side members or supports 24. The feed-rolls 12 and 13 are shown designed to tension the work-sheet against the platen to prevent displacement of the work-sheet when it is line-fed. The paper-shelf 14 extends rearwardly of the platen and terminates in an upper curled or rolled edge 15. A shaft 16 is operatively secured to the outer side of the paper-shelf 14 by the arms 23, and embracing this shaft are two spaced-apart collars 17 carrying pivots 18 upon which are fulcrumed the clamps 19 that curve around the rolled edge 15 of the paper-shelf. It will be understood that the collars 17 are slidably and adjustably mounted upon the shaft 16. The clamps 19 have plates 20 formed as continuations thereof, which plates are held under tension in contact with the opposite side of the paper-shelf 14. Formed upon each plate 20, along one edge thereof, is the integral guide-flange 21 which projects at right angles preferably to the plate 20 and formed at right angles integrally upon each guide-flange 21 is a lug or flange 22, this lug being disposed in parallel relation to the plate 20, as shown in Figure 1.

The plates 20 and clamps 19 form paper-guides as is well understood by those skilled in the art. A work-sheet in the form of a web A is unrolled from a source of supply 25 in the course of the line-spacing of the platen, and passes downwardly along the paper-shelf 14 and is engaged by the feed-rolls 12 and 13, so as to overlie the platen 10, and the work-sheet A then passes upwardly in front of the platen. The work-sheet is held the proper distance transversely of the paper-shelf 14 by means of the guides, the plates 20 of which underlie the sheet and the flanges 21 and 22 of which respectively complete a chute to hold the sheet against lateral and vertical displacement.

According to the present invention, the work-sheet or web is squared as it is fed upwardly by the platen during its line-spacing operation, and the invention provides for gaging this sheet and cutting a

printed form thereon from the next succeeding printed form.

Arranged to overlie so as to be detachably secured upon the side supports 24 of 5 the platen-frame is a pair of similarly sized and shaped standards 28 having right- angular bearing plates or flanges 26 secured by fasteners 27 upon said supports. These standards support a paper-table, a 10 gage-bar and a tearing-off knife; and should the width of the typewriting machine upon which this device is to be secured vary so that the standards have to be separated from each other a greater or lesser distance, it is provided that the standards be 15 adjustable towards and from the paper-table longitudinally.

Each standard 28 has an upstanding arm 29 formed thereon which is formed with 20 one of two rightangularly-disposed lugs 30 which project towards each other. Vertically-elongated slots 31 are formed upon portions 40 formed upon the opposite ends of a knife-bar 38, and projecting into these slots 25 31 are screws 32 which receive thumb-nuts 33, by means of which the knife-bar 38 may be vertically adjusted. Removal of the nuts permits removal of the blade. A paper-rest comes in the form of an elongated plate 34 30 which has an upper base-portion 34^a attached at its opposite ends 35 to lugs 30. Horizontal elongated slots 36 are formed upon the ends of base-portion or plate 34^a, and projecting in these slots 36 are screws 37 tapped into the lugs 30. These screws 35 adjustably hold the table 34 upon the standards 28, the adjustment being width- wise.

The main body-portion 34 of the paper- 40 rest inclines upwardly and rearwardly from the delivery side of the platen to the vertical portion 34^a; and formed upon the end of the plate 34 is a side-edge guide in the form of a rightangular flange 41. A gage- 45 bar 42 is secured angularly to the back of the paper-rest 34 and extends upwardly. Slidably and adjustably mounted upon this gage-bar is the gage-member 46, and this member is held in adjusted position by 50 means of the thumb-screw 47 engaging the gage-bar. The fasteners 43 secure the gage- bar upon the paper-rest.

One of the important features of the present invention consists in angularly disposing 55 the tearing-off throat with respect to the paper-rest. The knife-bar is formed as an intermediate portion of a metallic strap. Its ends 40 are twisted so as to be disposed diagonally of knife-bar 38, the twists 60 formed thereupon being designated 39. The screws 32 which secure the table upon the lugs 30 of the standards pass through the slots 31 and are tapped into the lugs 30. The ears lie flat against the lugs 30, which 65 dispose the knife-bar 38 at a bias with re-

spect to the vertical plate or table 34^a, said bar and plate forming a vertical throat, the table 34^a forming an obtuse angle to the table 34, the knife operating as a finger to press the web into the angle, bending the 70 web. This causes friction against the web, and holds the web steady during various operations thereon, and particularly keeps the web from falling loose from the knife.

To bring the cutting edge of the knife- 75 bar close to the rest, the knife-bar 38 is formed with suitably twisted ends 39. The plate is formed with terminal notches 50 to clear the screws 32 at the adjustment of the paper-rest.

The operation of the parts of the present invention is as follows: The web A has a succession of forms or orders printed thereon. The typist types upon any particular order-form any mail-order item handled by 80 any given department of the mail-order organization. After the order has been completely typed upon it is ready to be gaged so as to locate the division line between this order and the next succeeding and printed order along the edge of the tearing-off knife 38. The typist casts off the feed-rolls 12 and 13 from engagement with the platen. At this time the web is properly squared upon the paper-shelf 14 by means of the flanges 85 21 of the paper-guides, so that it cannot move transversely of this shelf, and the guards 22 prevent it from being displaced vertically therefrom. The web, after the feed-rolls are cast off, is trued relatively to the printing line by the co-operation of the guide-flanges 41 of the paper-rest with said side guides 21. With the web thus squared 90 with respect to the printing line, the typist takes hold of the leading edge of this web 100 and draws the first form thereon upwardly and into the mouth 51 formed by the rest and knife-bar 38. The web is passed between this knife and the rest above the cutting edge of the knife-bar where it may meet frictional resistance. The leading edge of this first form is brought into contact with the gage-member 46 which has been adjusted to correspond with the vertical adjustment of the knife 38, so that when the leading end 105 of the first form strikes gage 46, the division line between the first and second printed forms coincides with the cutting edge of the the tearing-off knife. This allows the typed first form to be cut off. The top edge of the second printed form remains held frictionally between the knife and the table 34^a, and is typed upon with another and different mail-order item than the first, and then 110 drawn upwardly, gaged and then shorn off as just described. The screws 27 are the same screws which now secure the end plates in position upon the platen side members. It is not necessary to reorganize or change 115 any part of the machine to which the inven- 120

tion is attached. The knife-bar 38 can be shifted vertically because of the slot-and-screw connection thereof with the rest to locate its cutting edge at the proper point 5 relatively to the varying lengths of forms so that the forms may be severed. The leading-edge gage 46 is then adjusted accordingly. Thus the distance from the knife edge to the gage 46 is brought into correspondence 10 with the distance between the knife edge and the printing line on the platen, so that said gage 46 accurately and finally locates the web for both severing the same and typing the first line on the second form. 15 The adjustment of gage 46 will be double the adjustment of the knife blade; that is, an increase of one inch in length of form will call for one inch lift of the knife-blade and two inches lift of the gage 46. The 20 guides 21, 41 form a chute or race which trues the web on horizontal lines, permitting rapid whisking of the web up to the gage 46, without danger of skewing.

Variations may be resorted to within the 25 scope of the invention, and portions of the improvements may be used without others.

Having thus described my invention, I claim:

1. In a typewriting machine, the combination 30 of a platen, a platen-frame upon which said platen is mounted, opposing side members carried by said platen-frame, a pair of standards having rightangular bearing plates removably secured upon said side members, 35 rightangular lugs formed at the upper ends of said standards, a knife-bar extending longitudinally of said platen and having its opposing ends formed with vertical slots, the slotted ends of said knife-bar overlying said 40 lugs, and set-screws projecting into said slots, tapped into said lugs and overlying said knife-bar to adjustably hold said knife-bar in position.

2. In a typewriting machine, the combination 45 of a platen-frame, a platen revolvably mounted therein, a paper-shelf in back of said platen, a paper-rest in front of said platen at the upper plane thereof, guides adjustably mounted on said paper-shelf, each 50 guide having a side flange with a rightangular lug bent over thereupon so as to be parallel with said shelf, a rightangular flange formed upon one end of said paper-rest and being in alignment with one of the side 55 flanges of one of said guides to position a sheet upon the platen, a tearing-off knife-bar mounted for adjustable movement upon said paper-rest, and means for securing both the knife-bar and the paper-rest upon said 60 platen-frame.

3. As a new article of manufacture, a 65 paper-rest consisting of an elongated plate, a paper-rest, a pair of standards each consisting of a bearing flange and a rightangular upstanding arm, a rightangular lug

formed upon each of said arms and projecting towards each other and overlying said rest at the upper portion thereof, a gage-bar secured at its lower end upon said rest, means for adjustably securing the ends of 70 said rest upon said lugs, a knife-bar extending longitudinally upon said rest, and means for vertically adjusting said knife-bar upon said lugs.

4. In a typewriting machine, the combination 75 of a platen-frame having opposing side supports, a pair of standards fixedly secured upon said side supports, a paper-rest consisting of a plate having its opposite ends supported upon said standards, a knife-bar secured at a bias with respect to said paper-rest with its cutting edge in proximity to said rest and with its blunt edge spaced therefrom a greater distance than said cutting edge, and means for vertically adjusting 80 the opposite ends of said knife-bar.

5. As a new article of manufacture, the combination 85 of a pair of standards, fastening means therefor, a paper-rest consisting of a plate, lugs projecting beyond the opposing ends of said plate, elongated slots being formed upon said lugs, lugs formed upon said standards overlying the other lugs, screws projecting into said slots and tapped into the standards, lugs to adjustably position said standards with respect to said other lugs, a knife-bar secured to said paper-rest, and a side rightangularly-disposed flange formed upon said rest at its end adjacent said first-mentioned lugs and 90 extending below said knife-bar.

6. In a typewriting machine, the combination 95 of a platen-frame having opposing side supports, a paper-rest consisting of a plate extending between said side supports, lugs extending beyond said rest, standards removably secured upon said supports and having lugs adjustably secured upon the other lugs, and means on said rest for cutting sheets which may engage said rest. 100

7. The combination of a paper-rest consisting of a plate vertically disposed, said plate having a downwardly and angularly disposed extension, a rightangular side flange formed upon said extension at one 115 end, a knife-bar held at a bias to said rest above said flange with its cutting edge nearest the rest, and means for fastening said rest upon a typewriting machine.

8. As a new article of manufacture, a 120 paper-rest consisting of a plate having a guide-flange formed at one end thereof, and a knife-bar extending longitudinally of said plate above said flange and supported at a bias thereto with its cutting edge nearest 125 to said rest and permitting the insertion of a sheet between said cutting edge and said rest.

9. As a new article of manufacture, a 130 paper-rest having a side flange for squaring

a sheet overlying said rest, an upwardly-extending gage-bar secured to said rest, a 5 slidable gage upon said bar engaged by the leading edge of said sheet, and a knife-bar extending longitudinally of said rest and adjustably supported at a bias thereto so that its blunt edge provides a mouth for the entrance of said sheet to said cutting edge and so that said cutting edge may frictionally engage said sheet for a severing action thereagainst.

10. As a new article of manufacture, a plate forming a paper-rest, oppositely-arranged supports for said plate, a knife-bar 15 extending longitudinally of said plate and having its ends offset so that said offset portions overlie said supports and dispose said knife-bar at a bias to said plate with its cutting edge nearest to said plate, said offset 20 portions being formed with vertical slots, and set-screws tapped into said supports and projecting into said slots for adjustably positioning the ends of said offset portions of said knife-bar.

25 11. The combination of a plate, standards supporting the opposing ends of said plate, rightangular lugs formed upon said standards, said lugs overlying said plate, a longitudinal bar consisting of terminals overlying said lugs, and an intermediate knife-bar integrally turned at a bias with respect to said terminals so as to incline downwardly with respect to said plate with its cutting edge nearest to said plate.

30 12. The combination of a plate, standards having lugs secured in overlying relation with the ends of said plate, a knife-bar extending longitudinally of said plate in front thereof, integral terminal ears formed upon 35 said knife-bar twisted diagonally of the axis of said knife-bar and overlying said lugs, said knife-bar being cut away at opposite ends to provide shoulders engaging the outer edges of said lugs in order to position the cutting edges of said knife-bar 40 nearer to said plate a distance less than the thickness of either of said lugs, and means for removably securing said ears upon said lugs.

45 13. In a front-strike typewriting machine, the combination with a platen and means for guiding a work-web to the platen, of a web line-feeding, jumping, locating, severing and truing device for forms of 50 different lengths, including a table erected at the delivery side of the platen, said table forming part of a web-race along which the web may be whisked manually alternately with its line-feeding operations, releasable 55 means to hold the web to the platen for line-feeding, permitting the web at will to be whisked through said race to make the jumps, and means at the top of said table for locating accurately and finally and severing 60 the web at the point at which the typing 65

of the next form begins, including a knife adjustable towards and from the printing line and also including an independently adjustable leading-edge gage for the web, said web-race in the form of a web-truing 70 chute including opposite side guides mounted upon said table and also opposite side guides mounted at the introductory side of the platen and registering with said table-guides, all of said guides co-operative with 75 one another for truing the web on transverse lines thereof relatively to both the severing means and the printing line on the platen, each of the opposite side guides on said table extending from the knife to the platen, 80 and of sufficient length to prevent skewing of the advanced web from its true path at right angles to the platen.

14. In a front-strike typewriting machine, the combination with a platen and means for guiding a work-web to the platen, of a web line-feeding, jumping, locating, severing and truing device, including a table erected at the delivery side of the platen, 85 said table forming part of a web-race along which the web may be whisked manually alternately with its line-feeding operations, releasable means to hold the web to the platen for line-feeding, permitting the web at will to be whisked through said race to 90 make the jumps, a severing device for the web, means at the top of said table a form's length in advance of the severing device, for locating accurately and finally the web 95 for severing and for typing the first line 100 of the next form, said web-race in the form of a web-truing chute including opposite side guides mounted upon said table and also opposite side guides mounted at the introductory side of the platen and registering with said table-guides, all of said guides 105 co-operative with one another for truing the web on transverse lines thereof relatively to both the severing means and the printing line on the platen, and a letter-feeding 110 carriage for said platen, each of the opposite side guides on said table extending from the knife to the platen, and of sufficient length to prevent skewing of the advanced web from its true path at right angles to the platen.

15. In a front-strike typewriting machine, the combination with a platen and means for guiding a work-web to the platen, of a web line-feeding, jumping, locating, 115 severing and truing device, including a table erected at the delivery side of the platen, said table forming part of a web-race along which the web may be whisked manually alternately with its line-feeding operations, releasable 120 means to hold the web to the platen for line-feeding, permitting the web at will to be whisked through said race to make the jumps, a severing device for the web, means at the top of said table a form's 125 length in advance of the severing device, for locating accurately and finally the web 130 for severing and for typing the first line of the next form, said web-race in the form of a web-truing chute including opposite side guides mounted upon said table and also opposite side guides mounted at the introductory side of the platen and registering with said table-guides, all of said guides co-operative with one another for truing the web on transverse lines thereof relatively to both the severing means and the printing line on the platen, and a letter-feeding carriage for said platen, each of the opposite side guides on said table extending from the knife to the platen, and of sufficient length to prevent skewing of the advanced web from its true path at right angles to the platen.

length in advance of the severing device, for locating accurately and finally the web for severing and for typing the first line of the next form, said web-race in the form 5 of a web-truing chute including opposite side guides mounted upon said table and also opposite side guides mounted at the introductory side of the platen and registering with said table-guides, all of said guides 10 co-operative with one another for truing the web on transverse lines thereof relatively to both the severing means and the printing line on the platen, each of the opposite side guides on said table extending from the 15 knife to the platen, and of sufficient length to prevent skewing of the advanced web from its true path at right angles to the platen, and a letter-feeding carriage for said platen, means being provided at said 20 severing device for frictionally detaining the leading portion of the severed web, to prevent it from falling away from the severing device.

16. In a front-strike typewriting machine, the combination with a platen, of a 25 web line-feeding, jumping, locating, severing and truing device, including a table erected at the delivery side of the platen, said table forming part of a web-race along 30 which the web may be whisked manually alternately with its line-feeding operations,

releasable means to hold the web to the platen for line-feeding, permitting the web at will to be whisked through said race to make the jumps, a severing device for the 35 web, means at the top of said table a form's length in advance of the severing device, for locating accurately and finally the web for severing and for typing the first line of the next form, said web-race in the form of 40 a web-truing chute including opposite side guides mounted upon said table and also opposite side guides mounted at the introductory side of the platen and registering with said table-guides, all of said guides 45 co-operative with one another for truing the web on transverse lines thereof relatively to both the severing means and the printing line on the platen, and a letter-feeding carriage for said platen, means being provided at said 50 severing device for frictionally detaining the leading portion of the severed web, to prevent it from falling away from the severing device, said detaining means including a plate at an obtuse angle to said table, and said severing device pressing the web into the angle and thereby frictionally holding the web against falling while permitting it to advance at the line-feeding operation.

JESSE A. B. SMITH.
